EMIL SCHAERER, OF GOLDACH, SWITZERLAND

TENTERING FRAME FOR THE WET TREATMENT OF FABRICS

Application filed July 28, 1930, Serial No. 471,377, and in Germany August 3, 1929.

The present invention relates to improvements in tentering frames for the wet-treatment of fabrics, such as dyeing, bleaching, creping and the like, and to which the fabric is pinned in zig-zag fashion along one of its edges. In the known frames of this type the distance between the bars supporting the pin carriers cannot be altered. In consequence thereof the fixed webs of fabrics cannot adapt themselves sufficiently to the treatment as only the shrinkage in the width of the fabric in the direction of the weft, and not the shrinkage in the longitudinal direction, in the direction of the warp, is considered. Devices of this type are not suitable for the mentioned treatment, particularly for creping.

The subject matter of the present invention is a tentering frame which overcomes the above mentioned drawbacks in as much as the bars on which the pin carriers are displaceably mounted are connected to screw threaded sleeves, the latter being adapted to be moved towards and away from each other by means of a hand crank and screw threaded spindles arranged along the side of the frame.

The pin carriers are so shaped that no injuring of the fabric may occur when the pin carriers abut against each other in the course of the treatment of the fabric or already when the latter is fixed to the frame and it is intended to save space; with the known devices the dyeing liquor has no access to the parts of the fabric present between the pin carriers. In order to avoid this drawback, according to another feature of the present invention those parts of the pin carriers in which the pins are fixed are made thinner than the other parts of the pin carrier by at least twice the thickness of the fabric.

Furthermore in contradistinction to the known devices the pin carriers are swingably arranged for the purpose of facilitating the removal of the fabric, whereby the folds on one or both sides of the removed web are maintained, and not for the purpose of tensioning the fixed webs; this tensioning is effected by displacing the bars on which the pin carriers are mounted.

50 A constructional example of the subject

matter of the present invention is illustrated on the accompanying drawings, in which

Fig. 1 is a side view of the frame with parts shown in section,

Fig. 2 is a vertical section along line 2—2 in Fig. 1,

Fig. 3 is a plan-view of Fig. 1 and

Fig. 4 shows details in a perspective view.

Referring now to the drawings the vat 5 is so subdivided by a partition wall 6 that the dyeing liquor may flow below and above the partition wall from one compartment of the vat to the other. The frame 7 is removably placed on the edge of the vat. On the longitudinal part 8 of the frame a shaft 11 adapted to be turned by means of a crank 10 (Fig. 3) is mounted in laterally arranged bearings 9. The turning motion of the shaft 11 is transmitted by means of bevel gearings 12, 13 to left and right hand threaded spindles 14 placed across the vat and turnably mounted in bearings 16 arranged on the longitudinal parts 8 and 15 of the frame. The nuts 17 co-operate with the threaded parts of the spindles 14 and are connected by means of braces 18 to sleeves 19. In the latter the bars 21 of approximately half round cross-section are mounted; the bars may be turned in the sleeves by means of levers 20. On these bars 21 the pin carriers 22 having a bore corresponding to the cross-section of the bar are mounted to be displaceable in the longitudinal direction of the bars. Pins 23 are provided on the outer facing of the pin carriers 22 and the web S is supported by these pins. The nuts 17 are provided with forks 24 pointing in the upward direction, guide rods 25 fixed with their ends in bearings 16 are inserted in the forks 24. On the transverse connections 27 and 28 of the frame handles 29 are provided.

The web of fabric S is advantageously fixed to the tentering frame when the latter is removed from the vat, to which end serve the handles 29. The web S, as is shown in chain-dotted lines in Fig. 3, is placed in zig-zag fashion around the pin carriers 22 of the two bars 21 and is held on its upper edge by the pins 23. Thereby it is intended that the web is held by the longitudinal tension applied to

it when it is placed on the pin carriers to prevent a tearing of the web at the parts where the pins penetrate the fabric. The latter should not be carried by the pins 23 but the pins should only prevent the fabric from slipping off the needle carriers 22. Those faces of the pin carriers 22 on which the pins are arranged are to be placed vertically by means of the levers 20 during the fixing of the web 10 to the frame. After the whole length of the web has been pinned to the frame, the tension in the single folds i. e. in the longitudinal direction (warp) is preferably somewhat increased by distancing the bars 21 from each other by means of the crank 10.

When pinning the web to the frame the upper longitudinal edge of the web is placed around the lower portion of the pin carriers 22 in which the pins 23 are arranged whilst 20 the upper portion of the carriers, which is thicker than the lower portion is not covered by the web. The magnitude of the difference in thickness between the upper and the lower portions of the pin carrier 22 is on each side 25 of the latter slightly more than the thickness of the treated fabrics. This smaller thickness has not the purpose of facilitating the removal of the fabric but to give the dyeing liquor unhindered access to the fabric also 30 when the pin carriers 22 abut against each other as is shown for two needle carriers in Fig. 4, in which case the web does not project between the upper portions of the pin carriers and is thus not excluded from the liquor. These relative positions of the pin 35 carriers may occur during the treatment, for instance by the action of the treatment liquor, however the pin carriers may also be placed so near to each other from the very beginning 40 of the treatment for the purpose of saving space in the vat.

When the fabric shrinks owing to the action of the liquor the above described device permits to adapt the shrinkage of the web 45 in the longitudinal direction of the web to that in the widthwise direction, whereby in comparison to the known devices a product of a better quality is obtained in a very simple manner; as with the known devices the shrinkage in the longitudinal and transverse directions of the web is the same. This 50 adaptation is obtained by adjusting the distance of the bars 21 from each other by means of the crank 21 to correspond to the widthwise shrinkage of the web, whereby the tension in the longitudinal direction is adjusted to conform with the required shrinkage.

The removal of the web from the frame 55 may be caused by turning the levers 20 so that the pins 23 are withdrawn from the fabric, whereby the latter sinks towards the bottom of the vat whilst maintaining its folded shape provided the flow of the liquor does not disturb the folds. Further only one of 60 the levers 20 may be turned so that the fabric

sinks only on one side down in the vat, whilst on the other side the web is still suspended by the pins, whereupon it is removed from the latter by hand so that the folds are maintained.

70

By means of a pump not illustrated in the drawings the liquor may be circulated from the lower part of the smaller separate space of the vat to the larger space of the latter as is well known in the art. Obviously heating coils may be provided in the vat.

75

I claim:

1. A tentering frame for the wet-treatment of webs of fabrics, comprising in combination, two oppositely arranged bars, pin carriers displaceably arranged on said bars and adapted to receive the web of fabric placed in zig-zag fashion from the carriers on one bar to the carriers of the other bar, screw threaded bushings to which said bars are connected, and screw threaded spindles cooperating with said bushings for altering the distance of said bars from each other.

80

2. A tentering frame for the wet-treatment of webs of fabrics, comprising in combination, two oppositely arranged bars, pin carriers displaceably arranged on said bars and adapted to receive the web of fabric placed in zig-zag fashion from the carriers on one bar to the carriers of the other bar, screw 85 threaded bushings to which said bars are connected, screw threaded spindles cooperating with said bushings, a shaft arranged along one side of the frame, a crank on said shaft, and means for transmitting the turning motion of said shaft to said screw threaded spindles for adjusting the distance of said bars from each other.

90

3. A tentering frame for the wet-treatment of webs of fabrics, comprising in combination, two turnably mounted bars arranged parallel to each other, a lever fixed to each bar for turning the latter, pin carriers displaceably arranged on said bars and adapted to receive the web of fabric placed in zig-zag fashion from the carriers on one bar to the carriers of the other bar, screw threaded bushings to which said bars are connected, and screw threaded spindles cooperating with said bushings for altering the distance of said bars from each other.

100

4. A tentering frame for the wet-treatment of webs of fabrics, comprising in combination, two turnably mounted bars arranged parallel to each other, a lever fixed to each bar for turning the latter, pin carriers arranged on said bars and displaceable in the longitudinal direction of said bars and adapted to receive the web of fabric placed in zig-zag fashion from the carriers on one bar to the carriers of the other bar, the portion of the pin carriers receiving the web being thinner by at least twice the thickness of the fabric than the other portion, screw threaded bushings to which said bars are connected,

110

115

120

125

130

and screw threaded spindles cooperating with said bushings for altering the distance of said bars from each other.

5. A tentering frame for the wet-treatment of webs of fabrics, comprising in combination two oppositely arranged bars, pin carriers displaceably arranged on said bars and adapted to receive the web of fabric placed in zig-zag fashion from the carriers on one 10 bar to the carriers of the other bar, that portion of the pin carriers which is situated between each fold of the fabric being thinner than the portion which is displaceably arranged on the bars, screw threaded bushings 15 to which said bars are connected, screw threaded spindles cooperating with said bushings, a shaft arranged along one side of the frame, a crank on said shaft, and means for transmitting the turning motion 20 of said shaft to said screw threaded spindles for adjusting the distance of said bars from each other.

In testimony whereof I have signed my name to this specification.
